CASING FOR AN ELECTRONIC DATA TERMINAL

William A. Sours, Sauquoit, N.Y., assignor to Cogar
Corporation, Wappingers Falls, N.Y.

Filed Jan. 8, 1971, Ser. No. 105,148

Term of patent 14 years

Int. Cl. D14—02

U.S. Cl. D26—5

FIG. 1

FIG. 2

FIG. 3

FIG. 4

FIG. 5

FIG. 6

FIG. 1 is a perspective view of a casing for an electronic data terminal showing my new design;

FIG. 2 is a top view of the casing for an electronic data terminal shown in FIG. 1;

FIG. 3 is a front elevational view;

FIG. 4 is a right side elevational view;

FIG. 5 is a left side elevational view; and

FIG. 6 is a back elevational view thereof.

I claim:

The ornamental design for a casing for an electronic data terminal, as shown.
